UNITED STATES PATENT OFFICE.

HENRY H. NORRINGTON, OF WEST BAY CITY, MICHIGAN.

PERFORATING-STAMP.

SPECIFICATION forming part of Letters Patent No. 249,975, dated November 22, 1881.

Application filed January 26, 1881. (No model.)

To all whom it may concern:

Be it known that I, HENRY H. NORRINGTON, of West Bay City, in the county of Bay and State of Michigan, have invented a new and 5 useful Improvement in Perforating-Stamp; and I do hereby declare that the following is a full, clear, and exact description of the same.

The object of my invention is to provide an improvement in the class of punches or perforating-stamps designed for use in banking and other similar establishments for the purpose of puncturing or cutting out portions of a check or other written instrument, and thereby preventing fraud by alteration of such instrument to cause it to express a higher value than was originally intended.

I have obtained Letters Patent of the United States for stamps or punches of this class, and the present invention is in the main an improvement upon that which forms the subject of Patent No. 223,161, granted to me on December 30, 1879.

The changes in construction and the new or added devices embodying the improvements 25 will be hereinafter described in detail; reference being had to accompanying drawings, forming part of this specification.

Figure 1 is a plan view, part of the head of the plunger being broken away. Fig. 2 is a 30 vertical transverse section on line $x-x$, Fig. 1, showing also a check or other paper secured on the table. Fig. 3 is a vertical longitudinal section on line $y-y$, Fig. 1. Figs. 4 and 5 are plan views of the under and upper sides respectively, of the disk to which the receiving-dies are attached. Fig. 6 is a plan view of the base of the stamp and the devices directly attached to it. Fig. 7 is a section on line $z-z$, Fig. 6. Fig. 8 is a detail sectional view, showing the attachment of the punches to the carrier.

The letter A indicates the table upon which the check or other paper X is laid to be punched, and over which it is drawn from right to left 45 by means of a feed-wheel, B, the paper being guided in such movement in a right line by fingers a, that are adapted for adjustment toward or from the front edge of the table. The said wheel B is arranged vertically beneath 50 the table A, and its roughened periphery works through a lengthwise slot in the same. The

paper is held down on the wheel by a spring-presser, C, so that it will have the requisite friction therewith to insure the required feed, or intermittent progressive movement imparted 55 to it by devices operated by the plunger E. From the base D of the stamp rises a tubular standard, in which said plunger E is arranged to slide vertically.

The above devices were embodied in my previous inventions, although in somewhat different form.

I will now indicate the additions and changes I have made in the construction and consequent operation of the stamp.

The plunger E is passed centrally through and is connected by groove and feather, Fig. 2, with a disk, F, that carries a series of vertical punches, b, arranged concentrically with its axis.

Directly above and parallel to the disk or punch carrier F is a second disk or punch receiver, F', which is provided with a series of holes, b', arranged concentrically with the axis, and also coincidently with the position of the 75 several punches b. These two disks F F' are rigidly connected by a central tube or hub or in any other suitable manner, and hence rotate together and with the plunger E, the latter being also free to slide vertically within the limits defined by the feather and groove; hence by turning the enlarged milled head c of the plunger E the disks F F' can be set in any required position.

The punches b are small solid cylinders and 85 slide vertically in their sockets. They project about one-third their length below the carrier F and are encircled by spiral springs e, which are fastened to the punches at the lower end. The function of these springs is to retract the 90 punches after having punched the paper.

To the under side of the upper disk, F', Fig. 8, are permanently attached a series of die-plates, one for each hole b' in the disk. These plates are cut with the figure of a star and 95 numbers from one to nine, inclusive, and also the cipher, (0.) On the upper side of the disk F' the same characters are inscribed, Fig. 3, immediately contiguous to the several holes b', which correspond to the dies or die-plates. 100 This inscription is for convenience of inspection by the operator, so that he may always

quickly adjust the die-carrier F to bring the required punches *b* successively to the front, in which position alone they can be operated to puncture the paper.

- 5 The heads of the punches *b* are cut with the same characters (stars and numerals) as the aforesaid die-plates or dies and are also adapted to fit accurately in the latter, but free to slide vertically, so that it may be forced up or 10 through the paper placed between the disks F F'. The device for raising the punches to cause them to do this work is a lever, H, which is pivoted on the bed of the stamp so that its head projects under the plunger E, which rests 15 thereon. This same arrangement was exhibited in my previous invention; but I have in this case provided a different form of spring, and also arranged it differently. Likewise, by the projection of the punches *b* below their carrying-disk F, I am enabled to dispense with a 20 finger or vertical projection on the front portion of the lever, which was previously required for the purpose of forcing up the punches. I further simplify the construction by employing 25 but one spring in place of two—that is to say, I employ a plate-spring, I, which is placed in guides or keepers *d* on the bed M of the stamp and arranged at right angles to the lever H. This spring is arched or curved upward, and 30 hence presses upward against the head of the lever H, so that the free or front end of the latter is depressed and the plunger E held normally elevated. When the plunger is forced down the spring I yields or bends downward 35 and the lever H is tilted, thus bringing its free end up against a punch, *b*, and forcing it through the paper, as will be readily understood.

The front end of the lever H has a lateral 40 arm which is connected with the feed-wheel B by means of a pawl and ratchet. The improvement over my former invention consists in this. As before, the ratchet forms an integral portion of the feed-wheel B, or is else 45 rigidly attached to it; but, instead of providing it with teeth on its periphery, the teeth *f* are formed on the side of the same contiguous to its edge and the pawl *g* is pivoted to swing laterally and held against the face of the wheel 50 by a spring, *h*, so that each time the lever H rises to force up a punch, *b*, the pawl *g* slides up and hooks over a tooth, *f*, and as the lever H resumes its original position the pawl draws down the tooth it has thus engaged, and there- 55 by rotates the wheel B and moves the paper a corresponding distance over the table A. This arrangement of parts—to wit, ratchet, pawl, and spring—insures their operation or regular coaction, so as to feed the paper in the 60 required manner, whatever be the speed or irregularity with which the stamp is operated.

Another improvement consists in applying a plate-spring, L, as shown in Figs. 2 and 6, so that it will not only serve as a stop to ar- 65 rest the motion of the punch-carrier F and hold it steady in the required position, but also announce to the operator, by a clicking

sound, when the carrier is properly adjusted with a punch, *b*, in front. Such spring L is secured at one end to the base M, and its free end is bent or curved sharply upward to form a projection of suitable form to enter between the ends of the punches *b*. When the die or punch carrier F is rotated the punches pass over the end of the spring and depress it; but 75 at each such passage a click or sharp sound is produced.

A further improvement consists in constructing the thumb lift or plate *k* of the clip or presser with a rear extension, which projects 80 beneath the rim of the disk or receiving-die F', Fig. 1, so that the thumb-lift cannot be raised so high as to weaken the spring, and thereby render it useless for its purpose. This feature is of much importance in the practical 85 use of the stamp.

I have also devised a new mode of securing or attaching the punches *b* to the disk or carrier F.

As shown in Fig. 8 the punches are provided with lateral studs *l*, and the carrier with vertical slots *m*, to receive the same. The slots open into the sockets of the punches and extend nearly to the top of the carrier, so that they limit the upward movement of the punches, as well as prevent their rotation.

To hold the punches *b* in their sockets and resist the tendency of the springs *c* to draw them downward, I apply a wire or other small band, *n*, to the carrier F, the same fitting in a 100 circumferential horizontal groove in the latter, as shown. This means secures the punches, and yet permits them to be conveniently removed when required.

Having now described my several improvements, I claim them as follows:

1. The combination, with the table and receiving-die, of the spring clip or presser having a thumb-lift which extends inward beneath the edge of the die, as shown and described, 110 for the purpose specified.

2. The combination of the rotating punch-carrier, the punches whose lower ends project below its under side, the springs encircling such projecting portions of the punches, and the lever arranged as shown, and having a flat head that acts on said punches for forcing them up at the proper time, as set forth.

3. The combination of the punch-carrier having sockets and vertical slots opening into the same, the punches provided with studs that project into and slide in the slots, and a band which encircles the carrier and prevents detachment of said punches, as well as supports them when not in action, as and for the 125 purpose specified.

4. The combination, with the plunger and rotating punch-carrier, the punch-lever H, and bed M, having pairs of keepers *d*, as specified, of the spring I, which is constructed of an arched metal plate and held in place by said keepers that embrace or form sockets for its ends, as shown and described.

5. The combination of the plunger, the lever

H, the pawl *g*, hinged thereto so as to swing laterally, the ratchet or hooked disk having teeth *f* projecting laterally from its inner side, the spring for holding the pawl pressed laterally against the ratchet, and the feed-wheel, all as shown and described, to operate as specified.

5. The combination, with the punch-carrier having punches that project from the under

side of the same, of the spring arranged, as 10 specified, to serve as a stop and produce a click to announce when the carrier is in proper position for operation.
